UNITED STATES PATENT OFFICE.

GEORGE E. BROWN, OF MADISON, WISCONSIN.

POLISHING-LAP.

SPECIFICATION forming part of Letters Patent No. 369,431, dated September 6, 1887.

Application filed October 4, 1886. Serial No. 215,305. (No model.)

To all whom it may concern:

Be it known that I, GEORGE E. BROWN, a citizen of the United States, residing at Madison, in the county of Dane and State of Wisconsin, have invented certain new and useful Improvements in Fabrics for Polishing-Laps; and I do hereby declare the following to be a full, clear, and exact description of the invention, such as will enable others skilled in the art to which it appertains to make and use the same.

This invention has relation to laps for polishing-tools of the class intended for imparting highly-polished and even surfaces to glass and other articles—such as, for example, lenses; and the object of the invention is to provide a lap having a surface that will receive, retain, and gradually pay out or deliver the polishing-powders and lubricants uniformly over its entire surface, so that it will greatly expedite the operation of polishing and impart a highly-finished surface to the article subjected to its action.

With these general objects in view, the invention consists in certain features of construction, hereinafter specified, and particularly pointed out in the claims.

Referring to the drawings, Figure 1 is a plan, portions being broken away, showing the several materials composing the lap. Fig. 2 is a lap constructed in accordance with my invention and cut into disk form. Fig. 3 is a vertical section of a polishing-tool of a form adapted to polish a lens, and provided with my improved lap; and Fig. 4 is a sectional view of the corrugated foil.

Like letters of reference indicate like parts in all the figures.

Heretofore the operation of grinding and polishing has been carried on by means of cast-iron tools having polishing-heads of brass, lead, &c., and in some instances the head of the tool has been provided with felt and cloth, thereby forming a polishing-lap for the reception of rouge or other polishing-powders. By experience it has been found that considerable time is consumed before a proper polish is obtained, and that a variety of tools are necessary for holding different grades of powders. Previous to this the contour of the head of the tool necessarily conformed more exactly to the curvature or irregular surface of the ar-

ticle to be polished. This, of course, required a great collection of tools of different sized and shaped heads. This objection is also overcome by my invention, and a single tool, be the head flat, concave, or convex, is made to conform within certain limits to and operate upon a surface of any shape whatever.

In order that a clear understanding of my invention may be had, I will proceed to describe the same in detail.

The essential element of my invention is the employment of malleable metal in sheet or foil form. This is cut to conform to the outline of the polishing-head of the tool and secured thereon by what is known in the art as "cement"—for instance, pitch, rosin, beeswax, &c., usually thinned with alcohol. In using a lap made of lead-foil I find that better results are obtained by interposing between the foil and tool-head a layer of some flexible material—such as, for instance, felt, leather, or cloth—and this more especially when an extremely high polish is desired. I have also discovered that in using a lap the outer surface of which is of foil, although good results are secured, still when rouge or other polishing-powder is applied with a lubricant it is likely to form in lumps and not spread evenly over the entire surface of the lap. This prevents the entire surface of the lap from coming in contact and operating upon the surface to be polished, and of course causes more time to be consumed in bringing the surface to the degree of polish desired. To obviate this, therefore, I corrugate the lead-foil or other polishing-surface, either by fine ribs crossing each other at regular or irregular angles or by concentric rings arranged to cross each other, or in any other design. By this means the polishing-powder and lubricant will be evenly distributed over the lap and as evenly imparted to the surface of the article to be polished. A lap thus formed imparts an extremely high even finish over the surface of the article, and a shorter time is required than heretofore by reason of the entire surface of the lap being always and uniformly in contact with the surface of the article.

When it is desired to use a finer grade of polishing-powder, the foil is removed and replaced by another and the finer grade of powder applied, this operation being repeated as

often as necessary, and requiring no cleaning of the lap, whereby loss of time is caused.

In order to adapt a single flat-surfaced tool, A, to both concave and convex surfaces, (see Fig. 3,) I first apply a layer of cement, B, and apply it to the surface of the article to be polished, either revolving the polisher or article, as desired. In this manner the cement is made to conform to the surface of the article to be polished. The foil C is then placed in position upon the cement and the lap is formed and ready for use.

If desired, a layer of cloth, leather, or felt, D, may be interposed between the head of the tool and the cement. Especially is this advisable where an extremely fine and highly polished surface is required, because this gives a very delicate yielding action to the lap upon the article.

Where a form of lap approaching a hemisphere is desired, it may be advisable to apply the foil thereof in separate strips, whereby a smooth surface of the lap is secured and no wrinkles or ridges formed in the foil, which latter would be the case were a single sheet forced to the form mentioned.

It is apparent that I may provide a material from which laps of any desired form may be cut, and to give the necessary firmness to the material I attach thereto a cloth or other similar flexible backing, D, (see Fig. 1,) upon which the cement B is spread and upon which is laid the foil.

In Fig. 3 the foil C is represented as plain, while in the other figures of the drawings it is represented as corrugated.

In Fig. 4 the cement B is placed upon the back of the corrugated foil, so as to fill the

concavities of the corrugations, whereby the corrugations are strengthened to withstand the pressure to which the foil is subjected when in use. The corrugated foil having the concavities in its back thus filled may be mounted directly upon the tool-head or upon a textile backing, the increased quantity of cement B, as shown in Fig. 3, being principally for the purpose of adapting the lap for conformation to irregular surfaces to be polished, and also to secure the foil to the cloth or tool-head.

Having described my invention and its operation, what I claim is—

1. A lap for polishing-tools, comprising a rigid foundation, a layer of cloth, felt, or other flexible material, a layer of cement, and a superimposed layer of corrugated foil, substantially as specified.

2. A lap for polishing-tools, comprising a layer of cement conforming to the surface of the article to be polished, and a layer of corrugated foil, substantially as specified.

3. As an article of manufacture, a fabric for forming polishing-laps, which consists of a flexible backing, a foil face, and an intermediate layer of cement, substantially as specified.

4. As an article of manufacture, a fabric for forming polishing-laps, which consists of a flexible backing, a corrugated foil face, and an intermediate layer of cement, substantially as specified.

In testimony whereof I affix my signature in presence of two witnesses.

GEORGE E. BROWN.
